James K. Davis

ATTORNEY

UNITED STATES PATENT OFFICE.

JAMES K. DAVIS, OF CHESTER, NEW JERSEY.

CRAYON-HOLDER.

1,286,551.

Specification of Letters Patent. Patented Dec. 3, 1913.

Application filed January 4, 1913. Serial No. 210,821.

To all whom it may concern:

Be it known that I, JAMES K. DAVIS, a citizen of the United States, residing at Chester, in the county of Morris and State 5 of New Jersey, have invented certain new and useful Improvements in Crayon-Holders, of which the following is a specification.

My invention relates to crayon holders which are particularly used in school-rooms.

10 The principal object of the invention is to provide a crayon holder which will always retain the crayon in writing position while the same is being used up, that is to say the device may be operated to project 15 the crayon from one end of the device as the former is being worn.

The second object of the present invention is to provide a holder of this general character which will effectively hold the crayon 20 and prevent the accidental disengagement of the same from the holder.

It is another object of the invention to provide a device of the above mentioned character which is effective and durable and 25 which may be operated easily.

Still another object of the present invention resides in the provision of a crayon holder which consists of a few parts, is inexpensive to manufacture and may be placed 30 upon the market at a nominal cost.

The above and other objects and advantages of the invention will be fully set forth and illustrated in the accompanying specification and drawings, and the inventive 35 features recited in the subjoined claim.

My invention consists of combinations, constructions, details and operations which will be herewith described and illustrated.

In the drawing, Figure 1 shows a side elevation of the crayon holder constructed in accordance with my invention.

Fig. 2 is a longitudinal sectional view of the same, part of the device being shown in elevation.

Fig. 3 is a transverse sectional view of the line 3-3 of Fig. 1, and

Fig. 4 is a like view taken on the line 4-4 of Fig. 1.

Referring in detail to the drawing where- 50 in one embodiment of the invention is disclosed, the numeral 5 denotes the barrel of my improved holder which is formed from a sheet of material that is bent in tubular form. The longitudinal edges of the barrel 55 5 are separated for a greater portion of their

length, and provide a longitudinal slot 6, the function of which will later become obvious. These edges meet at the outer end of the barrel to provide a stop 7. The barrel 5 embraces the crayon which is designated by the letter A which is illustrated in the drawing.

The numeral 10 designates the pusher or ejector of my device which is formed of any desired material.

Secured to the pusher or ejector 10, as at 11, is a resilient sleeve 12. This pusher 10, and sleeve 12 are slidably engaged in the barrel 5.

Projecting from the resilient sleeve 12 is 70 a pin 13, which is adapted for longitudinal movement in the slot 6. The stop 7 limits the movement of the pusher or ejector in one direction.

In assembling my improved holder, the 75 crayon is engaged in a resilient sleeve 12; the sleeve and crayon are then inserted in the barrel 5 so that the pin 13 projects within the slot 6. Thus it will be obvious that the crayon may be ejected from the barrel as it 80 is used up.

This disclosure is merely illustrative and it is to be understood that the construction herein illustrated and described may be modified in many different respects and that 85 my limits of modification are only governed by the subjoined claim.

Having described my invention I claim:

A crayon holder comprising a tubular casing open at each end and provided with a longitudinal slot, a solid pusher stem slidably disposed in said casing and projecting beyond one end thereof, a sleeve consisting of a single sheet of metal secured about said stem and extending slightly beyond the inner end thereof to provide a socket for the reception of a piece of chalk, and a fastening member securing said stem and sleeve together and projecting laterally for engagement with the slot formed in said casing, said fastening member providing a guide cooperating with said slot to guide the sliding movement of the stem and to prevent turning thereof.

In testimony whereof I affix my signature 105 in presence of two witnesses.

JAMES K. DAVIS.
